UNITED STATES PATENT OFFICE.

WILLIAM E. BALL AND ALICE C. BAILEY, OF ZANESVILLE, OHIO.

HARVESTER-CUTTER.

SPECIFICATION forming part of Letters Patent No. 540,623, dated June 11, 1895.

Application filed February 11, 1895. Serial No. 537,982. (No model.)

To all whom it may concern:

Be it known that we, WILLIAM E. BALL and ALICE C. BAILEY, citizens of the United States, residing at Zanesville, in the county of

5 Muskingum and State of Ohio, have invented certain new and useful Improvements in Cutter-Bars, of which the following is a specification, reference being had therein to the accompanying drawings.

10 This improvement relates to that class of cutter-bars where the cutters are attached to the bar by simply sliding them into a groove, and its object is to provide a strong, light and yet cheap cutter-bar; and to these ends the 15 invention consists in a cutter-bar made by folding a sheet of metal into three or more layers with the face and rear edges of one of the inner layers at a slight distance from the inner face and rear edge of the outside layers, whereby space is left to receive the bodies of the cutters and the flanges formed on the rear of said cutters. This form of cutter-bar has the advantage of being very light, yet strong, for the reason that there is so much 20 outside surface or skin on the metal of which it is made. It is well known that the exterior surface of metal, whether cast or wrought, is much the stronger, and especially is this so with rolled metal, for the action of the rollers 25 on the exterior of the metal condenses it to a considerable degree. Hence the advantage of using sheet-metal for the cutter-bar. We do not, however, broadly claim sheet-metal for this purpose, as we are aware that a sheet- 30 metal bar has before been used, but in that case the sheet-metal was simply doubled and the rear edge of the fold was slotted to receive the rear ends of the cutters. This cutter-bar was therefore comparatively weak, as the slots 35 in the rear not only weakened the bar but added to the expense of manufacture. In our improvement, on the contrary, the metal is not weakened by slotting the back, but the means used for holding the cutters in place 40 (the additional layer or layers) serve to strengthen the bar not so much by the additional metal, for the bar may be actually made lighter, but by the additional skin or surface of sheet-metal.

45 50 In the accompanying drawings, which clearly show our improvement, Figures 1 and

2 each represent a perspective view of a cutter-bar having cutters attached thereto in accordance with our invention. Fig. 3 is a perspective view of one of the cutters detached. 55

Referring now to the details of the drawings by letters—A represents a cutter-bar, which is formed of sheet metal and is bent or folded over onto itself so as to make (preferably) four thicknesses. A space a is left 60 between the last two thicknesses of the metal for the reception of the cutters B. The cutters B each have a down-turned flange b , which is arranged to slide in and out of the space a in the cutter-bar A in a manner which will 65 be readily understood. At one end of the cutter-bar the space a is plugged by a filling piece C which is secured between the folds of the metal of the cutter-bar by bolting, riveting, or in any suitable manner. On the 70 outside of the end in which the filling piece is secured, is attached an additional strip of metal D, on the end of which is an eye d which is adapted to be connected with the pitman by which it is driven. At the opposite end 75 of the cutter-bar is a screw-hole A', which is adapted to receive a screw a^2 for the purpose of holding the cutters in position.

After the cutter-bar is made as so far described, the cutters B may be slid one after 80 another in position, until the length of the cutter-bar is filled with the cutters, the first one inserted abutting against the filling piece and using it as a stop. Said cutters have holes or perforations b therein for the purpose 85 of inserting a hook, in order that the cutters may be drawn in or out. After the cutters are all in position, the screw a^2 is inserted, which single screw holds all of the cutters in 90 position, in a manner easily seen from an inspection of the drawings.

In Fig. 2, we have shown the eye d formed on the end of the filling piece D.

From the above and the accompanying drawings it will be seen that we have produced 95 a harvester cutter which may be used with any of the ordinary finger or guard bars, and which will allow of the ready removal and insertion of the cutters, should they need attention.

We do not limit ourselves to the number of folds of metal in the cutter-bar, as more

or less than four may be used. The number might be increased if a very strong bar were needed.

We are aware of the expired patent of Reed & Thompson, No. 136,266, dated February 25, 1873, and make no claim to anything therein shown, as the cutter-bar illustrated in said patent is described as of two pieces welded at the end and riveted along the back. Moreover, such cutter-bar would be very difficult to make at a reasonable cost without expensive machinery (unless made of cast-iron which is unfit for the purpose), whereas ours can be made by simply folding sheet-metal into the proper form.

What we claim as new is—

A cutter-bar comprising an integral piece of sheet-metal folded into a plurality of lay-

ers, with one or more layers inclosed in two outer layers, the face and inner edge of one of the inner layers being at a slight distance from the inner face and edge of the outer layer, thus leaving a horizontal space for the reception of the body of the cutters and another space at the rear of the inner layers for the reception of the flanges of said cutters, substantially as described.

In testimony whereof we affix our signature, in presence of two witnesses, this 5th day of February, 1895.

WILLIAM E. BALL.
ALICE C. BAILEY.
